UNITED STATES PATENT OFFICE.

MAHLON E. LAYNE, OF HOUSTON, TEXAS.

PUMPING MECHANISM.

1,211,457.

Specification of Letters Patent. Patented Jan. 9, 1917.

Application filed September 29, 1914. Serial No. 864,026.

To all whom it may concern:

Be it known that I, MAHLON E. LAYNE, a citizen of the United States, residing at Houston, in the county of Harris and State 5 of Texas, have invented certain new and useful Improvements in Pumping Mechanisms, of which the following is a specification.

The invention relates to pumping apparatus, and particularly to apparatus involving 10 the use of a rotary or centrifugal pump operated by an inclosed line shaft supported by bearings and requiring lubrication. The primary object of the invention is the provision of means whereby the leakage of oil 15 from the inclosed line shaft and into the pump casing is prevented when the pump is not running, thus conserving the oil and preventing the water from being charged with oil when the pump first starts. Certain 20 embodiments of the invention are illustrated in the accompanying drawings wherein—

Figure 1 is a vertical section through a pump mechanism supplied with my improvement, Fig. 2 is an enlarged detail section taken at the stuffing box in the pump casing, Fig. 3 is a plan view of the check valve member below the pump casing, and Fig. 4 is an enlarged detail section of a modification of the structure of Fig. 3.

30 In the ordinary centrifugal or rotary pump construction for use in lifting a supply of water to the surface of the ground for irrigation or other purposes, the drive shaft is supported in what is known as a shaft casing, which extends from the pump to the surface of the ground, and provides, not only for the support of a plurality of bearings for the shaft casing, but also constitutes a conduit whereby lubricant supplied to the 35 upper end of the casing is conducted to the various bearings along the shaft and to the upper bearing in the pump casing. This lubricant is fed downward by gravity, and by the suction produced in the pump by the 40 pump runners, so that while the pump is running these various bearings are supplied with the proper amount of oil, such oil being eventually discharged into the water in the pump casing and carried to the surface 45 of the ground with it to the discharge casing. When the pump is stopped and the water in the discharge casing and pump casing runs back to the suction pipe of the pump, there is nothing to prevent the lubricant, of which several feet may have collected at the bottom of the shaft casing, from

gradually leaking down into the pump casing, so that a large quantity of oil is wasted and when the pump starts the water of the well is charged with this large quantity of 60 oil, which is objectionable. It is the purpose of my invention to do away with this loss of oil when the pump is not running, by the provision of means which will stop the downward discharge of the lubricant 65 during the periods of rest, while at the same time permitting the proper downward feed of oil as heretofore described when the pump is running.

Referring to the drawings, the principal 70 parts of the apparatus illustrated in Fig. 1, may be enumerated as follows. 1 is the outer casing of a two-stage rotary pump provided with the sets of runners 2 and 3 secured for rotation to the pump shaft 4; 5 is the discharge casing of the pump leading to 75 the surface of the ground and discharging the water from the pump through the outlet 6; 7 is the shaft casing also extending from the pump casing to the surface of the ground 80 and provided with a plurality of bearings, one of which 8, is illustrated; 9 is a pulley by means of which the pump shaft 4 is rotated from a source of power; 10 an oil supply means leading up to the upper end of 85 the shaft casing 7; and 11 is the suction pipe of the pump, such pipe leading to the lower end of the pump casing.

Just below the bearing 12 in the neck of the pump casing is the stuffing box illustrated in enlarged detail in Fig. 2, such stuffing box comprising the collar 13 secured to the shaft by means of the set screw 14 and a gland 15 beneath which packing is provided in order to prevent the passage of water along the shaft 4. Slidably and loosely mounted on the shaft 4 beneath the collar 13 is a second collar 16, to the lower surface of which is secured a diaphragm 17, which serves to divide the space in the pump casing beneath the bearing 12 into two chambers 18 and 19. The collar 16 cooperating with the collar 13 acts substantially as a check valve, and when the parts are in the position indicated in Fig. 2, the passage of 100 liquid from the chamber 18 to the chamber 19 is prevented. On the other hand, when the collar 16 is moved so that its upper surface does not contact with the collar 13, then a free passage is afforded along the 105 shaft from the chamber 18 to the chamber 19. It will be seen that when the collar 16

is held up against the collar 13 in the position indicated in Fig. 2, the downward flow of oil from the shaft casing 7 and from the chamber 18 is prevented. The means whereby this engagement between the two collars is effected when the pump stops will now be described.

Located intermediate the lower end of the pump casing 1 and the upper end of the 10 suction pipe 7, is a check valve coupling member 20, such member being provided with a number of perforations as indicated in Fig. 3, such perforations being provided with sleeve members 21 carrying bolts 22. 15 Intermediate the heads of the bolts and the sleeves 21 are the check valves 23 yieldingly held in position by the springs 24. The type of check valve employed is immaterial, as any other type of check valve permitting 20 the upward passage of the water but preventing its reverse movement may be employed. The purpose of this check valve construction at the lower end of the pump casing, is to provide for a hydrostatic head 25 in the pump casing 1 and the discharge casing 5 sufficient to operate the check valve 16 when the pump is stopped.

When the pump is in operation, the check 30 valve 16 and the check valve 23 do not affect either the flow of the water to the pump casing or the feed of the oil to the discharge casing to any appreciable extent. The rotation of the runners produces a suction adjacent the shaft casing so that the liquid in the 35 chamber 19 beneath the diaphragm 17 is fed downwardly and mixes with the water as it discharges upwardly through the pump casing. The pressure on the lower side of the diaphragm 17 is thus less than on the upper 40 side, and as a result the collar 16 is held with its upper face separated from the lower face of the collar 13, thus permitting a flow from the upper side of the diaphragm to the lower side. A continuous feed of oil from 45 the shaft casing and along the bearing 12 is thus provided for. When however, the operation of the runners is stopped, the improvement heretofore described and involving the two check valve devices comes into 50 play. At this time the check valve 23 below the pump casing closes, thus trapping the water thereabove in the pump casing and in the discharge casing 5. A considerable water pressure is thus secured in the pump casing, and, due to the loose fit of the drive 55 shaft 4 and its bearings, this pressure is communicated to the chamber 19 below the diaphragm 17, thus forcing the diaphragm upward and causing contact between the collar 16 and the collar 13. Connection between the chambers 18 and 19 is thus cut off, so that while the pump is in its condition of rest no further flow of oil can occur from the shaft casing 7 to the chamber 19 below 60 the diaphragm 17. No oil is therefore

wasted while the pump is not in operation and when the pump does start there is no accumulation of oil in the water as it first flows from the pump. The arrangement has the further additional advantage that when the pump starts up again, the water immediately begins to flow from the outlet 6 since the water in the casing extends almost to this level when the pump is started.

The check valve construction illustrated in Fig. 2 is only one of a number which might be employed. Fig. 4 illustrates a slightly different construction in which a piston with a cup leather is substituted for the diaphragm 17 of the construction of Fig. 2. In this construction of Fig. 4 the stuffing box member 13' is the same as in the other construction, and the member 16' corresponds to the collar 16 of Fig. 4, such member 16' fitting loosely upon the pump shaft 4' as in the other construction. The member 16' reciprocates in the cylinder 25 and a cup leather 26 is employed to prevent a passage of liquid from one side of the member 16' to the other, when the parts are in the position of Fig. 4. This cup leather is clamped in position by means of the collar 27, forced up by the nut 28. It will be understood that the hydrostatic head as secured by the use of the check valves beneath the pump casing would be more or less effective to prevent a downward flow of oil without the oil check valve, and that the oil check valve might be held yieldingly in closed position by other means aside from the employment of the hydrostatic head, if so desired, my invention being of relatively broad scope with respect to these features, and not limited to their employment in conjunction, although this is preferable.

A stub shaft 29 is screwed to the central portion of the check valve coupling member 20, having its upper end projecting above the support to receive the lower end of the pump runner 3, which is provided with a cup shaped bearing 30 fitting over the projecting end of the stub shaft. The stub shaft serves to hold the pump shaft and runners properly centered, and is lubricated by oil supplied through the pipe 31 extending from the top of the wall and connecting with the oil passage 32 bored in the stub shaft 29. This passage supplies oil to the upper end of the stub shaft, thereby thoroughly lubricating all wearing surfaces of the bearing.

A valve 33 near the bottom of the pipe 31, operated by the wire 34 extending to the top of the well, controls the supply of oil necessary for the bearing. Because the bearing bushing 30 is closed at the top and is in the form of an inverted cup, regardless of the water pressure, no water can be forced upward between the stub shaft and the bushing while there is oil lubricating the bushing, and therefore no sand in the surrounding water can enter the bushing. The life

of the bushing is considerably increased by such construction.

What I claim is:

1. In combination, a pump casing, runners therein, a shaft for rotating the runners, a shaft casing provided with bearings for the shaft and adapted to carry a supply of lubricant, a discharge casing leading upward from the pump casing, and a check valve held closed when the runners are not rotated and adapted to prevent a flow of lubricant from the shaft casing to the pump casing below the valve at such time.
2. In combination, a pump casing, runners therein, a shaft for rotating the runners, a shaft casing provided with bearings for the shaft and adapted to carry a supply of lubricant, a discharge casing leading upward from the pump casing, a bearing for the shaft at the upper end of the pump casing, means for supplying lubricant to the shaft casing for said bearing, and a check valve below the said bearing held closed when the runners are not rotated and adapted to prevent a flow of oil into the pump casing below the valve at such time.
3. In combination, a pump casing, runners therein, a shaft for rotating the runners, a shaft casing provided with bearings for the shaft and adapted to carry a supply of lubricant, a discharge casing leading upward from the pump casing, a check valve exposed on one side to the pressure of the oil in the shaft casing and on the other side to the water pressure in the pump casing, and a second check valve for preventing a back flow of water through the pump casing when the rotation of the runners is stopped whereby a head of water is secured at such time sufficient to maintain the first mentioned check valve closed.
4. In combination, a pump casing, runners therein, a shaft for rotating the runners, a shaft casing provided with bearings for the shaft and adapted to carry a supply of lubricant, a discharge casing leading upward from the pump casing, and means, including a check valve for preventing a back

flow of water through the pump casing for maintaining a head of water in the discharge casing, when the rotation of the runners is stopped, sufficient to counterbalance the head of oil in the shaft casing and prevent a down flow of oil at such time.

5. In combination, a pump casing, runners therein, a shaft for rotating the runners, a shaft casing provided with bearings for the shaft and adapted to carry a supply of lubricant, a discharge casing leading upward from the pump casing, a bearing for the shaft at the upper end of the pump casing, a collar secured to the shaft below said bearing, a second collar loose on the shaft and adapted when held against the first collar to act as a check valve, means coöperating with the second collar for separating the space in the casing above such collar from the space in the casing therebeneath, and means whereby the second collar is made to contact with the first collar when the runners are not rotated.

6. In combination, a pump casing, runners therein, a shaft for rotating the runners, a shaft casing provided with bearings for the shaft and adapted to carry a supply of lubricant, a discharge casing leading upward from the pump casing, a bearing for the shaft at the upper end of the pump casing, a collar secured to the shaft below said bearing, a second collar loose on the shaft and adapted when held against the first collar to act as a check valve, means coöperating with the second collar for separating the space in the casing above such collar from the space in the casing therebeneath, and a check valve below the runners for preventing a back flow of water through the pump casing when the rotation of the runners is stopped.

In testimony whereof I have hereunto signed my name in the presence of the two subscribed witnesses.

MAHLON E. LAYNE.
